UNITED STATES PATENT OFFICE

FRANK KUSTERLE, OF KENOSHA, WISCONSIN, ASSIGNOR TO SIMMONS COMPANY, OF NEW YORK, N. Y., A CORPORATION OF DELAWARE

SPRING SUPPORT FOR BED BOTTOMS AND THE LIKE

Application filed October 2, 1926. Serial No. 139,072.

This invention relates to spring supports for bed bottoms and the like and more particularly to an improvement in means for positioning wire members such as coil springs which constitute part of a spring bed bottom.

The objects of the invention are to provide a support of the above described class having means for positioning a coil spring or other wire part, which means will be effective to rigidly support the part in the desired position; to provide such means without materially affecting the strength of the support; to provide such means by an improved method which may be easily and inexpensively carried out; and in general, to provide an improved structure of the class described.

Other objects and advantages will become apparent when reference is had to the following specification when considered in connection with the accompanying drawings, wherein I have illustrated a selected embodiment of my invention and in which:—

Fig. 1 is an elevation of a portion of a bed bottom showing the method of assembling the parts concerned in the present invention.

Fig. 2 is a section on the line 2—2 of Fig. 1.

Figs. 3 and 4 are more or less diagrammatic illustrations of the method of producing a spring seat according to the present invention, and

Figs. 5 and 6 are edge views of the bed bottom spring supporting member shown respectively in Figs. 3 and 4.

Referring now to the drawings and more particularly to Fig. 1, I have illustrated a portion of a bed bottom comprising a supporting frame 10 on which is supported a slat or cross member 11 which is preferably a metal strap of considerably greater width than thickness and arranged with its width extending in a vertical direction. The cross member 11 is preferably disposed at a distance below the supporting frame 10 so as to provide ample room for a coil spring of considerable expanded length without unduly raising the height of the top of the bed bottom. The cross member 11 may be so supported by means of an upwardly extending portion 12 and an outwardly extending

portion 13 which may be secured to the supporting frame by any suitable means such as riveting, the end of the slat being twisted 90° so as to facilitate such riveting. It is to be understood that the supporting frame 10 represents one side of the spring bed bottom and that there are a series of cross members 11 extending across substantially the entire width of the bed bottom and similarly supported on a similar supporting frame at the other side of the bed bottom.

Intermediate the supporting side frames of the bed bottom, I provide a plurality of rows of spaced coil springs in accordance with well known practice, one of which springs is indicated at 14. In the present instance, I have shown the coil spring 14 as being of the inverted conical type and having its small end supported on the slat 11. In order to position the spring and to prevent its moving from its position, I provide a pair of seats or notches 15 and 16 in the edge of the slat which are adapted to receive diametrically opposite portions of the bottom coil 17.

The springs may conveniently be locked to the respective slats by means of a tie wire as 21 which is threaded over portions of the lower coil 17 on opposite sides of the slat 11 and under the slot, as best shown in Fig. 2. I also prefer to provide a seat or notch 22 adapted to receive and position the said tie wire 21 as will be readily understood from an inspection of Fig. 1. The tie wire 21 extends the entire length of the bed bottom, being threaded through the successive coils and slats as above described and this serves to space the slats and so consolidate the spring supporting grille.

According to previous practice, seats or notches as above described have been provided by removing V-shaped portions of metal from the edge of the slat for example, as shown in the Locklin Patent No. 720,715. This practice is found to materially weaken the slat, sometimes as much as 50%, wherefore it has heretofore been necessary to provide a slat of considerably greater size to insure sufficient strength than is required as a result of the present invention.

In carrying out the present invention, I provide spring receiving seats without materially varying the cross sectional area of the slat throughout its length and thereby without materially affecting the strength of the slat. I accomplish this preferably by increasing the thickness of the slat as shown at 18 adjacent the seat and gradually reducing the increased thickness to the normal thickness as shown at 19. I contemplate increasing this thickness and gradually reducing the same as above described so that the cross-sectional area of the bulges of metal in any one vertical plane will be substantially the same as the cross-sectional area of the notch in the same plane. It will be apparent that the cross-sectional area of the slat is thus maintained substantially constant throughout its entire length. I have found that I can conveniently and economically produce such seats by swaging portions of the slat adjacent its edge out of their normal position and causing the displaced metal to bulge outwardly on both sides of the slat.

In Fig. 3 I have diagrammatically illustrated one means for carrying out this swaging operation and which means comprises a punch 25 and a die 26. The die 26 preferably consists of a member having a bifurcated end which is adapted to straddle the cross member 11. The ends of the bifurcated portion of the die member are provided with a substantially V-shaped notch 27. The die member is adapted to assume a position such as shown in Fig. 4 where the notch 27 is near the edge of the cross member in which the seat is to be formed. The punch member 25 is preferably provided with a wedge-shaped end as shown at 28 and preferably corresponds in some degree to the V-shaped notch 27 in the die member. The punch member is adapted to be brought down into engagement with the edge of the slat 11 and forced downwardly to displace a portion of the metal at the edge of the slat as will be readily understood from an inspection of Fig. 4, and as shown at 29 and 30 in Fig. 6. The die member 26 may obviously be made effective to limit displacement of the metal to a comparatively small area below the punch and to cause the displaced metal to bulge outwardly on either or both sides of the slat, whereby the width of the seat, as shown at 31 in Fig. 6, becomes almost twice the thickness of the slat 11. It is obvious of course that the thickness of this seat may be varied by varying the shape and depth of the notch.

By thus displacing as distinguished from removing, portions of the metal, I retain substantially all of the original strength of the slat. Where the cross-sectional dimensions of the slat are reduced in one direction, they are increased in another as the metal is caused to bulge outwardly adjacent the seat. This bulging has a strengthening effect sufficient

to substantially compensate for the weakening due to the reduction in the one direction.

Since I am thus able to produce a slat having suitable spring receiving seats formed therein, without materially weakening the slat, it is obvious that I may employ slats of considerably less thickness and weight than has heretofore been practicable and which correspondingly lowers the cost thereof as well as the weight of the article of which the slate forms a part.

Other seating arrangements may be readily produced by punching or swaging and will be comprehended by those skilled in the art and I, therefore, do not wish to be limited to the specific form shown. I am aware that various changes may be made without departing from the essence of the invention as defined by the following claim, which I desire to have construed as broadly as possible consistent with the state of the art.

I claim as my invention:

In a bed spring including a series of axially vertical coil springs, means for supporting the springs comprising a relatively wide but thin metal strap disposed on edge and having a series of notches swaged in its upper edge for receiving portions of a series of springs to position the same on the support, the metal displaced in forming said notches being disposed adjacent the bottom and sides of the respective notches so as to maintain the cross sectional area of the strap substantially uniform throughout its length.
